WATER SYSTEM

John Werner Ornell, Philadelphia, Pa.

Application June 25, 1940, Serial No. 342,220

3 Claims.

(Cl. 137—79)

This invention relates to water systems such as are commonly included in municipalities for the purpose of supplying individual households with water.

At the present time municipal water systems ordinarily include a single main from which water is drawn into each house to supply both the hot and cold water of the particular house. With the now known systems, the presence of a water heater in a house gives rise to a condition in which water backs up into the main as an incident to increased pressure, due to raising of the temperature of the water by the heater. When the water is thus backed up into the main, impurities are often carried with it which have contaminated the water supply.

The present invention has in view, as its foremost objective, the elimination of this backing up of water as an incident to operation of the household water heaters. In carrying out this objective the invention proposes the provision of a water system which comprises a supply main from which branches off a pair of auxiliary mains for each row of houses. One of these auxiliary mains will be the source of supply for water which is to be heated by the heaters in the houses.

An important object of the invention is the inclusion of a one-way check valve at the joinder of the hot water auxiliary main to the supply main. With a one-way check valve so included, any backing up of water which ordinarily might be caused by the operation of the household heaters is precluded.

The increase of pressure in the water as an incident to the rise in temperature thereof is inevitable. Accordingly, provision must be made for this increased pressure in the water. Ordinarily it is not practical to accommodate the increase of pressure in the faucets, or other outlets in the house, and the invention, therefore, has in view, as a further object, the provision of a water system of the character above noted in which a so-called riser is connected with the hot water auxiliary main. This riser provides a column of water which may fluctuate with changes in pressure of the water in the hot water auxiliary main.

The other auxiliary main will supply the cold water to the several houses, and being connected directly to the supply main, entirely independently of the hot water auxiliary main, it is impossible for the water in the cold water auxiliary main to become contaminated from any condi-

tions which might exist in the hot water auxiliary main.

Another somewhat particular object of the invention is the provision of a water system of the character above noted which includes a one-way check valve at the joinder of the hot water auxiliary main to the supply main, together with instrumentalities for testing said one-way check valve as occasion demands to insure of the proper operation thereof, and which instrumentalities may also accommodate the removal of the check valve for repair or adjustment should occasion demand.

Various other more detailed objects and advantages of the invention will in part become apparent, and in part be hereinafter stated, as the description of the invention proceeds.

The invention, therefore, comprises a water system which consists of a supply main. A pair of auxiliary mains branch off from the supply main, one of the auxiliary mains being intended to supply cold water, while the other auxiliary main is intended to supply the water that is to be heated. The joinder of the hot water auxiliary main to the supply main includes a one-way check valve, while suitable means, such as a riser, is associated with the hot water auxiliary main for accommodating changes of pressure of the water therein.

For a full and more complete understanding of the invention reference may be had to the following description and accompanying drawing, wherein

Figure 1 is a perspective view, largely diagrammatic, of a portion of a water system which is designed in accordance with the precepts of this invention, and

Figure 2 is an enlarged detailed view of the one-way check valve and associated instrumentalities.

Referring now to the drawing, wherein like reference characters denote corresponding parts, and first more particularly to Figure 1, a row of houses is represented at R, each house in the row R being identified by the reference character 10. In order to meet the requirements of everyday household use each of the houses 10 must include hot and cold water. A heater is, therefore, represented diagrammatically at 11, for heating water that is to be used in each house 10.

A supply main is shown at 12, and this supply main will take water from the reservoir or other source of supply, for the particular municipality in which the system is installed. Branching off

from the supply main 12 is a hot water auxiliary main 13, and a cold water auxiliary supply main 14; the auxiliary mains 13 and 14 being designed to supply the water for the houses 10 of the row R.

Conduits 15 connect the cold water auxiliary supply main 14 with the cold water system in each house 10, while other conduits 16 connect the hot water auxiliary supply main 13 with the water heater system represented at 11.

At a point conveniently close to the joinder of the hot water auxiliary main 13 to the supply main 12, and in the auxiliary main 13, is a one-way check valve designated V. This valve V is designed and arranged to permit water to flow from the supply main 12 into the auxiliary main 13, but positively prevents any backing up of water from the auxiliary main 13 into the supply main 12. This valve V may be any of the known one-way check valves found suitable for the particular purpose required thereof. The invention has particularly in mind an arrangement including a hand operated gate valve that will be located on each side of the check valve V. One of these gate valves is shown at 17, and the other at 18. These gate valves 17 and 18 may be operated in appropriate manner to test the check valve V, and they also may be closed to permit of the removal of the check valve V for adjustment or repair.

When the heaters 11 of the houses 10 are operated to increase the temperature of the water, the pressure of the water will increase, and arrangement must be made for relieving this increased pressure.

In accordance with this invention the relieving means is associated with the hot water auxiliary main 13, and takes the form of a riser 19 that is connected to the auxiliary main 13 as by the conduit shown at 20. This riser 19 takes the form of a vertical tube or pipe which may be suitably arranged and extends up a sufficient height so that a column of water included therein may fluctuate with variations in pressure of water in the auxiliary main 13.

In testing the valve V the gate valve 17 immediately adjacent the supply main 12 will first be closed, after which the petcock at 21 may be opened. If the valve V is functioning properly, only that amount of water which is included between the valve V and the gate valve 17 will come out of the petcock 21. However, if the test should

indicate that repair or adjustment in the valve V is required, the same may be removed by closing both the valves 17 and 18.

While a preferred specific embodiment of the invention is hereinbefore set forth it is to be clearly understood that the invention is not to be limited to the exact constructions illustrated and described, because various modifications of these details may be provided in putting the invention into practice within the purview of the appended claims.

I claim:

1. In combination, a plurality of houses that are to be supplied with water and each including a water heater, a water system for supplying water to the houses consisting of a supply main, a cold water auxiliary main, a conduit extending from said cold water auxiliary main to each house, a hot water auxiliary main, a conduit extending from said hot water auxiliary main to the water heater of each house, and a one-way check valve included in said hot water auxiliary main for preventing water passing from said hot water auxiliary main to said supply main.
2. In combination, a plurality of houses that are to be supplied with water and each including a water heater, a water system for supplying water to the houses consisting of a supply main, a cold water auxiliary main, a conduit extending from said cold water auxiliary main to each house, a hot water auxiliary main, a conduit extending from said hot water auxiliary main to the water heater of each house, a one-way check valve included in said hot water auxiliary main for preventing water passing from said hot water auxiliary main to said supply main, and means associated with said hot water auxiliary main for relieving increase of pressure of water therein.
3. In combination, a plurality of houses that are to be supplied with water and each including a water heater, a water system for supplying water to the houses consisting of a supply main, a cold water auxiliary main, a conduit extending from said cold water auxiliary main to each house, a hot water auxiliary main, a conduit extending from said hot water auxiliary main to the water heater of each house, a one-way check valve included in said hot water auxiliary main for preventing water passing from said hot water auxiliary main to said supply main, and a riser connected to said hot water auxiliary main.

JOHN WERNER ORNELL.
